UNITED STATES PATENT OFFICE.

HERMANN KRANTZ, OF AACHEN, PRUSSIA, GERMANY.

PROCESS OF DYEING ELONGATED BODIES OF YARN OR THE LIKE.

1,257,886.

Specification of Letters Patent. Patented Feb. 26, 1918.

Application filed April 8, 1914. Serial No. 830,332.

To all whom it may concern:

Be it known that I, HERMANN KRANTZ, a subject of the King of Prussia, residing at Aachen, No. 2 Monheimsallee, in the Kingdom of Prussia, Empire of Germany, have invented certain new and useful Improvements in Processes of Dyeing Elongated Bodies of Yarn or the like; and I do hereby declare the following to be a full, clear, 10 and exact description of the invention, such as will enable others skilled in the art to which it appertains to make and use the same.

In dyeing elongated bodies of yarn or the 15 like, such as hanks or skeins of yarn, it is common practice to string the bodies close beside each other upon horizontally arranged sticks in such manner that approximately their entire length depends loosely 20 below the sticks. The stringing up must be done very carefully and by skilled men in order to prevent the loose hanging threads from being engaged and rent by the laterally projecting heads formed at the ends of the 25 yarn sticks which owing to the frequent cooking have become rough and fissured. Special care is required with yarn which strongly frizzles. When dyeing by means of downwardly flowing dyeing liquid, the 30 lower ends of the hanks or skeins were supported by a kind of bottom *i. e.* the weight of same was balanced, in order to facilitate the penetrating of the dye liquid into the 35 spots of the hanks where they rested on the sticks. In order to avoid entangling of the threads when dyeing hanks in hanging state by means of reversibly circulating dyeing liquid, the hanks—especially those of lighter 40 yarns—were packed from the sides and kept down by a second stick pushed through the 45 hanks above their lower ends. According to the length of the hanks the sticks below were adjustable in height in order to allow the hanks some play over the two rows of 50 sticks. Thus at both flows (up- or downward) of the dyeing liquid the hanks were dyed in a stretched state, the whole yarn block moving in the direction of dye liquid and exposing to same the spots where it 55 rested on the sticks. On account of the continuously stretched state of the hanks, however, a good penetration of the dye liquid into the hanks is made difficult.

According to the present invention, when 55 dyeing hanks with reversibly circulating dye liquid, the single hanks which hang

freely in the vat on stick-like supports are no longer strung upon one or even two sticks, but are laid over such stick-like yarn bearers in such a way that their middle parts 60 rest at two spots on the yarn bearers and that their ends hang down on the right and left hand side of the sticks as loops. Above the bearing sticks at some distance from the same a stopping sieve or stopping boards 65 are arranged in any ordinary manner.

In order to illustrate the effect of the new way of supporting the hanks, this is shown on the accompanying drawings in combination with a generally known dyeing apparatus.

Figure 1 shows the hanks laid over bearing sticks in the new manner if the dye liquid is flowing downward.

Fig. 2 is a similar view with the dye liquid flowing upward.

Figs. 3 and 4 show front- and side-views of hanks laid over the bearing sticks in the new manner.

In the well-known way stopping boards 3 80 are placed in the dye liquid above the bearing sticks 2. When the dye liquid is moving upward the hanks are carried against these boards in order to be swelled. A bottom 85 below the hanging hanks for supporting same if the dye-liquid is moved downward is not provided in the dye vat and not necessary besides.

The stick-like yarn bearers may have the 90 form of sticks, strings, wires, little leather straps, bands, or the like; instead of being directly fastened to the dye vat they can be attached to the bearing frame which is put into the dye vat.

According to the new process, the hanging 95 up is considerably facilitated and the dyeing effect favorably influenced. With the new manner of laying the hanks over the yarn bearers, the surface with which each hank lies on these bearers is twice as large as when the hanks are strung upon the sticks. Consequently the downwardly moving dye liquid 100 easily penetrates into these spots so that it is not necessary to balance the weight of the hanks by a supporting bottom. Since 105 this mode of suspending the hanks arranges twice as much material cross-wise to the current as the ordinary suspension, the uprising liquid is more effective to spread apart the strands to form, as shown by Fig. 2, a loose 110 layer of yarn below the stopping boards 3. Owing to this manner of working the over-

laid hanks can be dyed, especially in the direction of the yarn bearers, without being packed from the sides and various large quantities can be treated in one apparatus.

5 As after each change of the direction of the dye liquid the threads of the hanks receive quite another position from one another, they are uniformly dyed.

10 The overlaying of the hanks is a simple work which can be quickly done by unskilled men without the loosely hanging threads being rent. Besides, the examination of each hank with regard to the right position of the threads at the binding-up thread is 15 unnecessary.

The advantages connected with the new process are:

Saving of time and wages for the laying over and taking off of the hanks,

20 Sparing of hanks,

Obtaining of loose yarn to be easily reeled,

Uniform coloring,

Applicability of one apparatus for small and large quantities.

25 Having thus described my invention, what I claim is:—

1. The herein described process of dyeing elongated bodies of yarn or the like, which consists in hanging said bodies substantially by their intermediate portions, over a supporting member, so that their opposite ends hang loose on the opposite sides of the supporting member, and then causing the dyeing liquid to flow in a vertical direction 30 through said yarn.

25 2. The herein described process of dyeing elongated bodies of yarn or the like, which

consists in hanging said bodies, substantially by their intermediate portions, over a supporting member, so that their opposite 40 ends hang loose on the opposite sides of the supporting member, and then causing the dyeing liquid to flow alternately upwardly and downwardly through said yarn.

3. The herein described process of dyeing 45 endless hanks of yarn or the like, which consists in doubling the hank over a supporting member, so that the two looped ends of the hank lie contiguous, and then passing the dyeing liquid through said yarn.

4. The herein described process of dyeing an elongated body of yarn, which consists in hanging the yarn by its intermediate portion over a suitable support within a vat, and then passing the dyeing liquid alternately 50 upwardly and downwardly through the vat.

5. The herein described process of dyeing an elongated body of yarn or the like, which consists in folding said body upon itself into substantially U-shape so that the ends of the 60 legs of the U will present the yarn in a relatively non-folded condition as compared with the connecting portion of the U, and then causing the dyeing liquid to flow through said yarn in a direction longitudinally of the legs of the U.

In testimony whereof I have signed my name to this specification in the presence of two subscribing witnesses.

HERMANN KRANTZ.
